GOLF PUTTING GAME DEVICE

Edward A. May, 11716 12th Ave. NE., Seattle, Wash.

Filed Nov. 13, 1962, Ser. No. 72,487

Term of patent 3½ years

(Cl. D34—5)

Fig. 2.

Fig. 3.

Fig. 4.

FIGURE 1 is a top perspective view of a golf putting game device with a part broken away and arranged in offset relationship, showing my new design;

FIGURE 2 is a plan view thereof;

FIGURE 3 is a side elevational view thereof;

FIGURE 4 is a longitudinal sectional view of a portion thereof taken on line 4-4 of FIGURE 2.

The dominant features of my design reside in the portion shown in full lines.

I claim:

The ornamental design for a golf putting game device, substantially as shown and described.
